UNITED STATES PATENT OFFICE

CARL F. GOUDY, OF FLUSHING, NEW YORK, ASSIGNOR TO PARENT RADIO CORPORATION, OF NEW YORK, N. Y., A CORPORATION OF DELAWARE

ELECTRIC PHONOGRAPH

Application filed April 11, 1928. Serial No. 269,073.

Special objects of the present invention are to provide an improved mounting for the electric reproducer and to provide such mounting in a form adapted for use with phonographs of standard construction in converting the same to electrical operation.

The foregoing general objects and certain more specific objects are attained by novel features of construction, combinations and 10 relations of parts as hereinafter defined and broadly claimed.

The drawing accompanying and forming part of this specification illustrates one practical commercial embodiment of the invention, but it should be understood that the structure may be modified as regards this disclosure without departure from the true spirit and scope of the invention.

Figure 1 is a broken side and part sectional 20 elevation of the apparatus.

Figure 2 is a vertical sectional view of the post or pedestal as taken on substantially the plane of line 2—2 of Figure 1.

Figure 3 is an enlarged cross sectional view 25 of the adjustable screw mounting for the reproducer. Fig. 4 is a broken detail of a support for other forms of pick-ups.

The reproducer indicated generally at 5 is shown of the electromagnetic type covered 30 in certain copending applications and having a magnetic reed terminating in a socket 6 carrying a needle 7 engaging the record 8 on the turntable 9 of the phonograph.

The back of this reproducer unit is shown 35 in the present disclosure as having a rearwardly extending tubular screw stud 10 through which the cord 11 extending to the amplifying apparatus passes and which screws into a socket 12 in a sleeve or collar 40 13 fitted in the end of the tubular supporting arm 14.

In order that the reproducer may be secured in the proper upright relation, the collar is shown as having a rotary adjustment 45 in the supporting arm provided by the shouldered portion 15 entered in the end of the arm and having circumferentially spaced screw seats 16 receiving a set screw 17 entered through an arcuate slot 18 in the arm. It 50 will be seen that with this construction, when

the reproducer or pick-up unit is screwed tight into the collar, the collar may be adjusted to bring the unit into upright relation and that if the length of the arcuate slot is not sufficient for this adjustment, the screw 55 may be removed and be inserted in whichever one of the screw seats then lines up with the slot.

The supporting arm 14 is mounted for both vertical tilting and lateral swinging movement by being secured at 19 in the mouth of an arm 20 which is pivoted horizontally at 21 to a plate 22 riveted at 23 to the upper end of a sleeve 24 which is rotatably seated in a vertical bore in the post or pedestal 25.

The rearward end of the arm 20 is weighted as indicated at 26 to balance or partially balance the weight of the reproducer unit. This construction permits of the supporting arm being made of sufficient length for securing the best results from the reproducer. The pedestal is preferably made sufficiently heavy to hold itself in place on the baseboard 70 of the phonograph so that the apparatus may be installed by the simple act of locating it 75 in proper position. If desired, the cord may be carried down through the phonograph base, which latter may have an opening 27 for this purpose.

The swinging action of the arm is preferably controlled to prevent it swinging too freely. In the illustration this control is effected by a dished spring 28 on the lower end of the bearing sleeve and frictionally engaging the face of a cavity 29 in the base 85 of the pedestal, the tension of this spring being regulated by a nut 30 screwed on the lower end of the sleeve and held by a lock nut 31.

The end of the counterbalancing arm 20 90 is shown as of inverted U-shape in cross section to receive the end of the supporting arm and to provide the spaced sides 32 forming an open ended yoke pivoted on the upper end of the vertical bearing sleeve. The supporting arm is releasably secured in this yoke by the screw 19, which construction permits the parts to be readily assembled and taken apart. The sides of the yoke are preferably parallel, 95 as shown, and spaced wider than the head of 100

the post so as to clear the post in the vertical tilting movements of the arm.

With the construction described, the reproducer unit is balanced so as to bear with the proper force on the phonograph record and is controlled as to its swinging movement so as to hold the needle properly engaged with the record groove. The holding tension can be readily adjusted by simply turning over the base and tightening or loosening the nuts controlling the spring pressure. The device is readily installed on any phonograph and is in fact an attractive addition to the phonograph, the attractive effect being enhanced by the fact that there is no exposed wiring. The latter feature is an advantage from mechanical and electrical standpoints since the conductor cord, protected as it is all the way, cannot be broken or injured by careless handling of the apparatus.

The parts are readily assembled or taken apart as may be required. In assembling, the screw socket 13 may first be screwed over the stud on the back of the reproducer unit and then be inserted in the end of the supporting arm, the screw 17 being passed through the slot 18 into engagement with the screw socket 16 which may happen to align with the slot.

30 The pivot 21 which forms the support for the tone arm may conveniently be in the form of a pin extended through the sides of the member 20 and through the up-turned pivot lugs 33 on the edges of the plate 22.

35 The tubular portion 14 of the tone arm may be of relatively light tubular stock, and where it is cut out at 34 for the passage of the conductor cord, it may be reinforced by turning in the ribs or flanges 35 at the edges of such cut out portions.

40 In order that the arm may be used for supporting other kinds of pick-up units, the construction illustrated in Fig. 4 may be provided, the same consisting of a lug 36 pivotally held to the end of the arm by a screw 10^a inserted into the screw socket 12 in place of the screw lug on the back of the unit 5. This lug is shown as having a tubular extension 37 of a size to receive the supporting clamp of the pick-up unit, and therefore provides a means for mounting such pick-up units. The securing of lug 36 by screw 10^a permits said lug to be swung from one side 45 to the other to suit different forms of pick-ups, some of which have the mounting clamp on one side, and others have the mounting clamp on the other side.

45 At times it may be desired to use the device for cutting phonograph records. For this operation, additional weight on the phonograph needle may be required, and this can be readily supplied by slipping a slotted weight 38 over the tubular portion of the arm, which weight can be slid along the arm

50 to the position where the required force is applied to the record.

What is claimed is:

1. In electric phonographs, a vertically swivelled tubular member, a horizontally pivoted arm on the upper end of said member, said arm having a tubular forward end portion, an electric reproducer unit on the forward end of said arm, an electric conductor cord extending from said reproducer unit through the tubular portion of said arm and down the vertically swivelled tubular member and adjustable spring means acting on said vertically swivelled tubular member to control the laterally swinging action of the reproducer unit. 70

2. In electric phonographs, a pedestal having a vertical bore and a recess in the base of the pedestal at the lower end of said bore, a sleeve journaled in said bore, a head on the upper end of the sleeve, a horizontally pivoted arm mounted on said head, an electric reproducer unit carried by said arm and spring tensioning means acting on said sleeve and located in the recess in the base of the pedestal for governing the laterally swinging movement of the reproducer unit. 85

3. In electric phonographs, an electric reproducer unit having a tubular screw threaded portion on the back of the same, a swinging supporting arm having a cooperating tubular screw threaded portion in the end of the same and a conductor cord extending from the reproducer unit through said cooperating screw threaded members. 95

4. In electric phonographs, a swivelled arm having a tubular forward portion terminating in a screw seat, an electric reproducer unit having a tubular screw threaded stud engaged in said screw seat and a conductor cord extending from said reproducer unit through the tubular stud and the tubular portion of the swivelled arm. 105

5. In electric phonographs, a swivelled arm, a screw socket adjustably seated in the end of said arm, an electric reproducer unit having a screw stud engaged with the socket and means for securing the screw socket in various angular relations in the end of the arm. 110

6. In electric phonographs, a swivelled arm having a tubular end portion with an arcuate slot in the side of the same, a screw socket rotatably socketed in the end of the arm and having a screw seat in line with the slot in the arm, a screw extending through the slot and into said screw seat and an electric reproducer unit having a screw stud engaged in the screw socket. 120

7. In electric phonographs, a swivelled arm, a screw socket swivelled in the end of said arm and provided with a plurality of screw seats, said arm having a slot in line with the screw seats, a securing screw extending through said slot into one of the 125

screw seats and an electric reproducer unit having a screw stud engaged in the screw socket.

8. In electric phonographs, a supporting arm consisting of a tubular forward portion and a weighted rearward portion, said rearward portion having an open forward end receiving the tubular portion, a vertically swivelled support, pivotal means securing the open part of the rearward portion of the arm to said support, a screw socket adjustably seated in the end of the tubular portion and an electric reproducer unit secured to said socket.
- 10 9. In electric phonographs, a pivotally supported counterweight having a socket in the forward end of the same, a tubular arm entered in said socket, an electric reproducer unit mounted on the end of said tubular arm
- 15 20 and having an electric conductor cord extending through said arm, said arm having the end portion thereof cut out to afford clearance for the conductor cord, and the side walls of said cut-out portions being
- 25 turned in to form flanges reinforcing the tubular structure.

10. In electric phonographs, the combination of an electric pickup unit, a supporting arm for said pickup unit, a vertically swivelled and horizontally pivoted mounting for said supporting arm, a fixed counterweight carried by said supporting arm on the opposite side of the pivotal mounting for balancing the weight of the pickup unit
- 30 35 and an extra adjustable weight slidable to different positions along the supporting arm to apply a load to the supporting arm at different points in the length of the same and independent of the counter balancing effect
- 40 afforded by the counterweight.

In testimony whereof I affix my signature.
CARL F. GOUDY.
